W. BISCHAN

MILK BOTTLE LOCK

Filed June 9, 1927

WILLIAM BISCHAN.
INVENTOR.

BY *Stuart Scharf*
ATTORNEY.

UNITED STATES PATENT OFFICE.

WILLIAM BISCHAN, OF BRONX, NEW YORK, ASSIGNOR TO BOT-LOK CO. INC., OF NEW YORK, N. Y., A CORPORATION OF NEW YORK.

MILK-BOTTLE LOCK.

Application filed June 9, 1927. Serial No. 197,579.

This invention relates to an improved milk bottle lock and it has for its principal object to generally improve upon and simplify devices of this class by producing one which is practical, one with which the milk bottle can be easily and quickly engaged or disengaged, and one which is comparatively inexpensive to both the manufacturer and the user.

Another object of the invention is to provide a milk bottle lock which embodies stationary and movable hinged members for gripping the neck of the bottle, together with novel means for holding unauthorized persons from disengaging the bottle from the device, the construction of the parts being such that the device can be placed on a door frame and adjacent the door so that the part in which the locking means is located, will be arranged in abutting relation with the door and will be rendered inaccessible when the door is closed.

A further object of the invention is to provide a device of this class embodying the aforesaid bottle engaging members together with novel locking means for said members, which means is ineffective until the bottle is placed in position and is then rendered automatically effective to hold the members against separation.

It is another object of the invention to provide bottle locking devices of this class which are such in construction that a number of them can be placed alongside of one another and in abutting relation, as will be hereinafter better described, whereby each device serves to render the locking means of the other adjacent device inaccessible.

A further object of this invention is to provide a bottle locking means wherein the part that forms the lock pin can also serve the purpose for holding notes to the milkman.

A further object of this invention is to provide an easily removable lock so that during the day the entire lock will be removed from the door-frame.

Other objects and advantages of the invention will be apparent during the course of the following description.

In accompanying drawing forming a part of this specification and in which like numerals are employed to designate like parts throughout the same:

Fig. 1, is an isometric view of the bottle lock.

Fig. 2, is a front view of the lock supporter. 55

Fig. 3, is a view taken on 3—3 of Fig. 2.

Fig. 4, is a plan view of the bottle lock in place.

Fig. 5, is a view of the latch when used for receiving a note. 60

As previously indicated the improved bottle lock is intended to be installed on a stationary part of the house adjacent a window or a door so that the latter will co-act therewith to render the locking means inaccessible so long as the closure is closed. This feature of the invention will be set forth more clearly as the description goes on, although, the device can be just as effectively used in connection with a window, I have shown it associated with a door. 65

Referring to the specification disclosure of the improved device it will be seen that it is composed of a pair of substantially duplicate symmetrical sections or members 1 and 2, the inner 1, of which is stationary and detachably mounted on the door-frame 3, the other section 2 is hinged to the first section at 4 and is adapted to be swung out to the position shown in Fig. 1 to enable the bottle 5 to be 70 engaged or disengaged whichever may be the case. 75

The section 1, is provided with a slidable bar 6 which is attached to the section 1 by means of a plate 7 and screw 8. 85

The section 1 is also provided with a latch 9 having a rounded nose 10, and pivoted on a pin 11, in a channel 12, attached to the section 1 at 13 and 14.

The section 2 is provided with a strip 15 revolving on a hinge 16 attached to the section 2 by a screw 17. The strip is also provided with a pin 18 which is adapted to enter an opening 19 in section 2. 90

Both the latch 9 and opening 19 are covered by projections 20 and 21 this is to prevent tampering with the mechanism when in operation. 95

The bar 6 slides into a bent plate 21^a having a slot 22. The plate is permanently affixed to the door-frame 3 by means of screws 23 through openings 24 and 25. 100

A spring 26 is affixed into the inner part of the section 2 by means of screws or other fastening means 27 and 28. 105

In operation, the slotted plate 21 is affixed into the door-frame, near enough to prevent the removal of the lock when in

place. The lock is slid into the slot 22 by means of bar 6.

If there is no bottle in place the lock is inoperative and the strip with its pin 18 can 5 be turned on the hinge to the position shown in Fig. 5 and used as a holder for notes to the milkman.

When the milkman comes and reads the note, turns the strip down, inserts the particular grade of milk between the sections 10 and closes the lock so that the latch 9 catches the pin 18, since the door 29 is closed, the milk cannot be moved from its place.

When the door 29 is opened the latch 9 can 15 be lifted and the lock opened and milk bottle removed.

From the foregoing description, it will be seen that I have devised a novel and simple device for locking milk bottles which will 20 prevent unauthorized persons from stealing or removing the bottle after it is placed in position in the device by the deliveryman. The parts of the device are in the form of simple castings which can be manufactured 25 at a comparatively low cost and can be retailed to dealers for comparatively small purchase price thus enabling them to furnish the devices free of charge to their consumers. In the end, the dealer will save by using 30 such a device because disputes with the consumers and dealers will be prevented and the dealer will not have to replace the stolen milk as is often the case. With the construction of device shown and described, 35 there is little or no danger of any of the parts becoming disarranged or getting out of order and little time is consumed in engaging and disengaging the milk bottle.

Furthermore, the device is applicable to either side of the frame of the closure which 40 is adapted to co-act therewith to render the locking means inaccessible. Other differences of construction distinguishing my device from prior patented and marketed ones used for the same purpose have doubtless 45 been made apparent from the description and drawings and the advantages accomplished by such differences have also been made clear.

Since probably the best results may be obtained with the construction and arrangement herein shown and described, this is taken as the preferred embodiment of the invention. However, I wish it to be understood that minor changes coming within the 50 scope of the invention as claimed may be resorted to if desired.

What I claim is:

A milk bottle locking device comprising a body for attachment to a door-frame to dispose one end thereof in abutting relation with the door, said body including stationary and movable members designed to engage the neck of a bottle, said body having a lock enclosure to be closed by the door, and co-acting locking means carried by said members and arranged on said enclosure, being accessible only when the door is opened, one of said locking means being a strip with a pin when downwardly arranged adapted to 60 engage a latch and when upwardly arranged 65 is adapted to receive notes.

Signed at N. Y., in the county of Bronx, and State of N. Y., this 26th day of May, A. D. 1927.

WILLIAM BISCHAN.
